V. BREDLIK ET AL

EXTRACTION OF SOLUBLE PRODUCTS FROM WOOD

Filed May 31, 1921

UNITED STATES PATENT OFFICE.

VLADIMIR BREDLIK AND LOUIS C. WHITON, JR., OF NEW YORK, N. Y.

EXTRACTION OF SOLUBLE PRODUCTS FROM WOOD.

Application filed May 31, 1921. Serial No. 473,805.

To all whom it may concern:

Be it known that we, VLADIMIR BREDLIK, a citizen of the Republic of Czechoslovakia, residing in the city, county, and State of New York, and LOUIS C. WHITON, Jr., a citizen of the United States, residing in the city, county, and State of New York, have invented certain new and useful Improvements in the Extraction of Soluble Products from Wood, of which the following is a specification.

In the separation of rosin, pine oil and turpentine from woods bearing these substances, such as cut pine, pine stumps, light wood, light tops, fir and spruce, the most common method involves steaming the wood to eliminate the volatile products and then extracting the soluble constituents with gasoline, heated in a vessel which is closed or nearly closed so as to maintain the pressure necessary to secure the required temperature. The heat involved in this and other processes produces certain decomposition products which contaminate the turpentine, and produces an inferior quality of rosin and pine oil, probably also on account of the decomposition products and certain products which are soluble in a hot solvent but not in a cold one.

By our process the temperature is or may be kept so low as to avoid these disadvantages and the products obtained are clear and transparent and practically the same as the commercial products produced from the gum directly. Our process also extracts a greater quantity of the constituents from wood than was possible under the previous process, or the same quantity with less solvent.

We accomplish this by a variation of pressure in the extracting operations. A volatile solvent is applied to the wood, previously cut into comparatively small pieces. The solvent for example may be benzol, turpentine, gasoline, carbon tetrachloride, acetone, alcohol, or the like. After a suitable interval of time we reduce the pressure on the solvent, the wood remaining in it. The pressure is reduced to a point below that at which the solvent is applied. Under the reduced pressure a certain amount of air or gas is released from the wood and bubbles rise through the solvent, stirring up the mate-

rial in the pores and cells of the wood so as to increase the extraction. Preferably we start, after applying the solvent to the wood, with a pressure considerably above atmospheric, and finish at atmospheric pressure. The solubility of the constituents in the wood is directly increased by reason of the pressure. We have found that with this application of pressure we do not have to disintegrate the wood to the same extent as is necessary without pressure, nor do we have to use as large a quantity of solvent to treat a given quantity of wood. The chipping of the wood into small chips is disadvantageous because it renders the mass difficult to work, and because the wood, after extraction is comparatively useless in making paper.

Following are examples of our process. A preliminary air pressure is applied to the wood before the solvent is introduced, such preliminary pressure being from 35 to 50 pounds per square inch above atmospheric. The solvent is then applied and the pressure raised to 100 pounds per square inch above atmospheric pressure. The pressure is applied mechanically in contradistinction to pressure caused by heating the solvent and throttling down the vapor outlet. The pressure may, for example, be obtained by the application of air pressure above the surface of the solvent or by filling the container with solvent and pumping in solvent at an increased pressure. After a suitable interval, depending on the character of the solvent and of the wood, the pressure is relieved and restored to atmospheric. The preliminary pressure causes the air in the wood to be put under pressure before the application of the solvent; and when the pressure is finally restored to atmospheric, the air thus initially compressed is liberated and disturbs the materials in the wood and exposes them more fully to the action of the solvent.

Or the solvent may be introduced at atmospheric pressure and the pressure be then increased to about 100 pounds per square inch above atmospheric, and released after a suitable interval. This process does not subject the air in the wood to pressure until after the solvent is applied, but it produces approximately the same excellent results.

A third method consists in first applying

the solvent, increasing the pressure to about 100 pounds above atmospheric and after a time relieving the pressure and further bringing it down to a point below atmospheric, that is to a partial vacuum. This results in drawing air out of the wood which was held therein under atmospheric pressure, and is analogous to the first example given above in which the air and the wood 10 was first compressed to a pressure greater than atmospheric.

In practice the relief of the pressure is accomplished by opening communication to a condenser so as not to waste the solvent 15 vapors. After the release of the pressure the solvent is drained off and subjected to any usual or suitable process for separating the solvent, turpentine, pine oil and rosin. The wood from which the solvent 20 has been removed will generally be subjected to a succession of treatments with solvent until the extraction has been accomplished to the extent commercially desirable.

An example of the working of the process 25 is as follows: 100 parts of resin-bearing wood chips are charged into a suitable container capable of withstanding pressure. An air pressure of 35 lbs. per sq. in. is introduced into the vessel, and 120 parts of 30 benzol, or a sufficient quantity to just immerse the wood at atmospheric temperature, is pumped into the tank, the pressure gradually increasing as the air in the tank becomes compressed. In case the pressure 35 has not reached 100 lbs., compressed air is added to bring it to this. After a period of 10 minutes the air pressure is relieved through a condenser or absorbent tower so as not to lose the benzol vapors contained 40 in the air. If the cover is taken off the pressure tank, it will be noticed that bubbles arise to the surface of the liquid.

The wood is then washed three times with one-fifth of the original quantity of benzol 45 each time to remove the solution of resinous material, and the residual benzol in the wood is recovered by steaming it. The degree of extraction will depend upon the character of the wood treated but will be considerably increased over that obtainable 50 by simple washes of benzol. As an example of this: Treatment of the wood in exactly the same manner as described above with the exception that atmosphere pressure is maintained throughout the operation left 6.5% resinous matter in the extracted wood chips; when treatment of the 55 same variety of wood was accomplished in the manner as described above, there remained 2.1% resinous matter in the extract- 60 ed wood.

Our process provides a practical method of applying a solvent to wood without any preliminary steaming, without the application of so high a temperature as to injure

the quality of the extracted constituents, with the possibility of using the wood in comparatively large pieces and with economy in the quantity of solvent used per ton of wood.

The accompanying drawing is a diagrammatic representation of an apparatus suitable for carrying out the process.

As will be apparent from the several legends on the drawing the application comprises in addition to the extractor, an air compressor and vacuum pump, a solvent pump and a solvent reservoir. The wood chips are placed in the extractor through the upper door 1 to about the level 2, resting on a perforated bottom 3. Compressed air is first pumped into the extractor by opening valves 4 and 5, say to a pressure of thirty-five to fifty pounds per square inch above atmospheric pressure. Valves 6 and 7 are then opened and the air compressor raises the pressure both in the extractor and in the solvent tank; the valve 6 opening the way to the solvent tank. The valves 4 and 7 are then closed, leaving the 90 valve 6 open. Also the valves 8 and 9 are opened to allow a circulation through the extractor and the solvent tank without loss of pressure and the solvent will flow by gravity from the tank into the extractor 95 until the material in the latter is entirely submerged in the solvent. Leaving the valve 6 open, and again opening the valves 7 and 4, the pressure is increased on the solvent say to 100 pounds per square inch 100 above atmospheric pressure; and the amount of pressure being controlled by the air compressor.

When the solvent has been left in contact with the wood for a sufficient length of time 105 the pressure is relieved by opening the valve 10.

This apparatus is substantially the same as that illustrated in connection with our Patent No. 1,372,479 of March 22, 1921, for 110 the extraction of fatty matter from garbage and other fat containing materials. The filling and emptying of the extractor and the application of the solvent and the variations of pressure thereon may be effected in different ways and described in the aforesaid patent. And it will be understood that this apparatus is only typical of many arrangements of extractor, solvent 115 tank and pumps and pipes which may be used to carry out the process. The steam inlet shown is for initially eliminating the more volatile products, whenever this is desirable.

Though we have described with great particularity of detail certain specific processes embodying our invention, yet it is not to be understood therefrom that the invention is restricted to the particular example given. Various modifications thereof in detail can 130

be made by those skilled in the art without departure from the invention as defined in the following claim.

What we claim is:

- 5 In the extraction of soluble constituents from wood, the method which consists in applying a preliminary air pressure above atmospheric to the cells of the wood, applying a volatile solvent and subjecting the

same to additional pressure without otherwise increasing its temperature and after a suitable interval of time relieving the pressure.

In witness whereof, we have hereunto signed our names.

VLADIMIR BREDLIK.
LOUIS C. WHITON, JR.
